UNITED STATES PATENT OFFICE

154,777

DESIGN FOR A SHOE OR SIMILAR ARTICLE

Alphons Hurzeler, New Rochelle, N. Y., assignor to Bally, Inc., New York, N. Y.

Application May 4, 1949, Serial No. 2,430

Term of patent 3½ years

(Cl. D7—7)

To all whom it may concern:

Be it known that I, Alphons Hurzeler, a citizen of the United States of America, residing in New Rochelle, county of Westchester, and State of New York, have invented a new, original, and ornamental Design for a Shoe or Similar Article, of which the following is a specification, reference being had to the accompanying drawing, forming part thereof.

The figure on the drawing is a perspective view of a shoe or similar article, showing my new design.

The opposite side of the shoe is substantially the same as the side shown.

I claim:

The ornamental design for a shoe or similar article, substantially as shown and described.
ALPHONS HURZELER.
